UNITED STATES PATENT OFFICE.

CHARLES GOLDSTEIN, OF CHICAGO, ILLINOIS.

DESIGN FOR A COVER FOR BRIDGE SCORE.

Application filed March 27, 1926. Serial No. 17,081. Term of patent 3½ years.

To all whom it may concern:

Be it known that I, CHARLES GOLDSTEIN, a citizen of the United States, residing at Chicago, in the county of Cook and State of Illinois, have invented a new, original, and ornamental Design for Cover for Bridge Score, of which the following is a specification, reference being had to the accompanying drawing, forming a part thereof.

The figure is a front perspective view of

a cover for bridge score, showing my new design.

I claim:

The ornamental design for a cover for bridge score, substantially as shown.

CHARLES GOLDSTEIN.
